CLAIM

The ornamental design for the baseball cap with 3D figure on bill, as shown and described.

DESCRIPTION

FIG. 1 is a front perspective view of a baseball cap with 3D figure on bill showing my new design;

FIG. 2 is a back perspective view of a baseball cap with 3D figure on bill showing my new design;

FIG. 3 is a perspective view taken from a left side angle of a baseball cap with 3D figure on bill showing my new design;

FIG. 4 is a perspective view taken from a right side angle of a baseball cap with 3D figure on bill showing my new design;

FIG. 5 is another perspective view taken from a left front side angle of a baseball cap with 3D figure on bill showing my new design;

FIG. 6 is a perspective view taken from a bottom right side angle of a baseball cap with 3D figure on bill showing my new design; and,

FIG. 7 is another perspective view taken from a right front side angle of a baseball cap with 3D figure on bill showing my new design.

The broken lines depicting hair on the figure illustrate portions of the baseball cap with 3D figure on bill that form no part of the claimed design.

1 Claim, 2 Drawing Sheets
